UNITED STATES PATENT OFFICE.

CLAES RYDEN, OF CRANSTON, RHODE ISLAND, ASSIGNOR, BY MESNÉ ASSIGNMENTS, TO UNIVERSAL WINDING COMPANY, OF BOSTON, MASSACHUSETTS, A CORPORATION OF MASSACHUSETTS.

WINDING-MACHINE.

1,205,270.

Specification of Letters Patent. Patented Nov. 21, 1916.

Application filed May 16, 1914. Serial No. 839,037.

To all whom it may concern:

Be it known that I, CLAES RYDEN, a citizen of the United States, residing at Cranston, in the county of Providence and State 5 of Rhode Island, have invented certain new and useful Improvements in Winding-Machines, of which the following is a specification.

My invention relates to winding machines 10 and consists particularly of an improved mechanism for applying pressure to the traverse-guide which traverses the material on the winding-spindle.

The object of my improvement is to provide 15 an adjustable pressure-device for applying resistance to the outward movement of the guide away from the winding-spindle as the winding increases in diameter, while allowing a relatively free movement of the 20 guide toward the spindle.

My improved pressure-means is intended particularly for use on machines employed in winding magnet or other coils for electrical purposes. For this purpose it is necessary 25 that the guide which effects the laying of the turns of wire on the coil be controlled very delicately and sensitively to maintain it in close relation to the surface on which the wire is being deposited, but 30 without contact therewith, so that unnecessary friction liable to cause abrasion of the insulation of the wire is prevented.

The method and means for carrying out 35 the invention are fully described in the following specification, illustrated by the accompanying drawings, in which like reference characters designate like parts.

In the drawings, Figure 1 is an end elevation of a traverse-guide of the type specified 40 showing my improved pressure-device applied thereto; Fig. 2 is a side elevation of the main portion of the guide pressure-means; and Fig. 3 is an end view of one form of coil as wound by the guide.

Referring first to Fig. 1, B designates the winding-spindle or arbor on which the coil C is wound and G is the guide which traverses the wire or other material back and forth and deposits it on the spindle. The 45 traverse-guide G may be of any usual form, but is preferably of the type shown and described in my United States Letters Patent No. 1,133,186, granted March 23, 1915. As 50

here shown it consists essentially of a pivoted arm g at the top of which is a bracket 55 g' carrying the main guide-roll or wheel g² and an auxiliary guiding pulley g³. The arm g is mounted at its lower end on a bushing or collar g⁴ which is free to turn and also to slide on a horizontal rod H. 60 The rod H is supported on the main frame of the machine, not here shown, and extends parallel with the winding-spindle B, thus serving as a track for the guide G as the latter is traversed longitudinally of 65 the spindle. The means for reciprocating the guide G along the rod H are not here shown or described as they may be of any usual arrangement and are not essential to an understanding of the present invention. 70

On the end of the rod H is mounted an arm or brace K which is held in place by a set-screw k. On the inside of the arm K is a flanged wheel or disk L which may be made integral with the arm, as here shown, 75 or constructed as a separate piece and attached thereto in any suitable manner. Mounted free to turn on the rod H is a hub m abutting the side of the wheel K and carrying a radial arm M. At the upper end 80 of the arm M is a hub or boss m' in which is secured a horizontal rod N extending parallel with the rod H. The rod N is here shown as being secured in the hub m' by a set-screw m², but it might be driven into the 85 bore of the hub or secured in any other suitable manner. The function of the rod N is to act as a guideway or track for the arm g of the traverse-guide G whereby pressure may be applied thereto from the guide 90 for the purpose hereinbefore specified. Referring to Fig. 1, one side of the rod N is adapted to bear against the face of the arm g which is formed with a hook or loop g⁵, adapted to partly encircle the rod. In this 95 manner the guide-arm g is prevented from swinging independently of the guiding-rod N and arm M, but is free to move with the latter about the common pivot H. The swinging movement of the guide G is thus controlled through the arm M, and the means for applying resistance to its movement consists of a friction-device operating in connection with the wheel or brake-disk L as next described.

Driven into a boss m³ on the side of the

2
arm M is a stud or pin m^4 to which is attached one end of a brake-band O. The band O is preferably constructed as a relatively thin strap of steel, or some other 5 wear-resisting material, and is adapted to encircle the periphery of the disk L while being held in place by the side flanges l, l. Secured to the free end of the band is a spring S, the opposite end of which is 10 hooked through a hole in the end of a stud T. The stud T passes through a lug m^5 which projects from the side of the arm M and a nut t on the end of the stud abuts the side of the lug to hold the stud against the 15 pull of the spring S. By turning the nut t the stud T can be adjusted in the lug m^5 and in this way the anchorage point of the spring S can be shifted so as to vary its tension and regulate the degree of friction 20 between the band O and the disk L.

Having now described the construction and arrangement of the parts of my new device its method of operation will next be explained: The wire w or other material 25 from which the coil C is wound is delivered from the supply-spool in such manner that it leads down to the traverse-guide G from above. As shown in Fig. 1, the wire w passes partly around and under the auxiliary guiding-pulley g^3 and thence partly 30 around and over the main guide-wheel g^2 to the winding-spindle B which rotates in the direction indicated by the arrow x. As the wire leads through the guide G there 35 will be a tendency for it to straighten out at w' as it passes on to the coil C. This tends to throw the guide-wheel g^2 slightly away from the surface of the coil and this tendency is taken advantage of to prevent 40 the guide from rubbing against the windings. That is to say, it is desirable to maintain the guide a slight distance away from the surface of the coil C so that as it traverses back and forth it will not rub on 45 the wire or other material to cause abrasion of its surface or injury to its insulating covering. At the same time it is most important that the guide G be maintained in close 50 relation to the periphery of the coil throughout the whole winding of the latter in order that the turns in the winding may be deposited precisely and accurately in exact 55 relation to each other. Now, as the layers of winding are built up concentrically on the core or spindle B and the coil increases in diameter this growth will act to force the guide-wheel g^2 away from the axis of the spindle while the arm g swings on its pivot H. During this rearward movement of the 60 guide the tension on the wire as it delivers from the supply is liable to vary considerably, due to irregularities of the winding on the supply-spool, and these variations will have a tendency to disturb the relation 65 of the guide to the surface of the coil C. To

check this tendency and prevent undue vibration or oscillation of the guide my improved pressure-device is designed to act through the arm M and rod N as follows: At the start of the winding the tension of 70 the spring S is adjusted to give a degree of friction between the brake-band O and disk L which is just sufficient to maintain the guide-wheel g^2 in close proximity to the surface of the coil C without allowing the 75 periphery of the wheel to bear on the coil. Now, as the coil C grows in diameter the guide-wheel g^2 will be forced gradually away from the axis of the winding-spindle and the swinging movement of the arm g 80 will carry the rod N and arm M with it through their connection at g⁵. This movement of the arm M is resisted by the friction of the band O on the disk L through 85 the connection of the band with the arm. It is to be noted that as the arm M turns in the direction indicated by the arrow y, Fig. 1, during the outward movement of the 90 guide G, the direction of pull on the band O will be against the spring S. That is to say, the pulling force of the band will act against the resilience of the spring and for this reason the resistance to the movement of the arm can be adjusted very delicately 95 as required. On the other hand, movement of the arm M in the opposite direction tends to loosen the band O on the disk L to decrease the friction therebetween, and therefore the guide G is allowed to swing toward 100 the axis of the winding-spindle with a freer movement than when it is receding from the spindle. In this way the outward movement of the guide is resisted to the required degree to maintain the wheel g^2 in close 105 relation to the winding without pressure tending to cause it to rub against the surface of the coil.

Various devices for applying resistance to the receding movement of the traverse-guide have heretofore been employed in the art, but usually these have been arranged with springs or weights acting directly against the guide. It is therefore believed that the present friction means is novel in its arrangement for resisting the outward 110 movement of the guide without applying pressure to force the guide in the opposite direction or toward the spindle. In other words, while the friction pressure-means acts to resist free outward movement of the 115 traverse-guide, it does not operate, as in the case of the usual spring or weight-loaded arrangement, to force the guide against the winding. For this reason the device is of great advantage for use in winding magnet 120 coils of fine enameled wire since it eliminates the usual rubbing action of the guide on the surface of the winding and therefore prevents chipping or scraping off the insulating 125 coating.

My new device is also particularly well adapted for winding coils of irregular shape. For some purposes it is advantageous to wind the coils on polygonal cores so that they can be applied to similarly-shaped parts of various and sundry electrical apparatus. For instance, Fig. 3 shows a coil C' wound on a rectangular center so that its periphery is of substantially the same contour. With my new pressure-means the traverse-guide is controlled in such manner that as the coil rotates during the winding process the guide is prevented from rebounding against the flat surfaces c' on its periphery after it has been forced away by the high points c², that is the corners of the coil. With the usual means for applying pressure to the guide the weight-loaded arms or direct-acting springs operate to carry the guide back against the surface of the winding after it has once been forced away by any irregularity on the periphery. To prevent this action it is necessary to provide dogging-means for restraining the guide from inward movement toward the axis of the winding-spindle after it has once been forced outwardly therefrom. In my present improved device the pressure-means acts as a resisting medium for controlling the outward movement of the guide without any tendency to carry it back toward the spindle and at the same time serves to provide a slight friction to hold the guide from too free backward movement. In effect, therefore, it is a combined pressure-means and dogging-device and hence is much more simple in construction and effective in operation.

Various modifications might be made in the form and structure of the parts of my new device without departing from the spirit or scope of the invention.

Therefore, without limiting myself to the exact construction shown and described, what I claim is:—

1. In a winding machine, the combination with the winding-spindle, of a traverse-guide adapted to recede from the spindle in accordance with the growth in diameter of the winding, and means operating to apply a constant degree of resistance to the movement of the guide away from the spindle and a less degree of resistance to its movement toward the spindle.
2. In a friction pressure-device for winding machines, the combination with the winding-spindle, of a traverse-guide adapted to recede from the spindle as the winding increases in diameter, and means to apply a constant degree of resistance to the movement of the guide away from the spindle and a less degree of resistance to its movement toward the spindle without tending to force the guide toward the spindle.
3. In a winding machine, the combina-

tion with a reciprocatable traverse-guide adapted to oscillate at substantially right-angles to its path of traverse, of means to resist the oscillating movement of the guide in one direction with respect to its traverse 70 while applying a less resistance to the oscillating movement of the guide in the opposite direction.

4. In a winding machine, the combination with a reciprocatable traverse-guide 75 adapted to oscillate at substantially right-angles to its direction of traverse, of friction means adapted to resist the oscillating movement of the guide in one direction while applying a less resistance to its move- 80 ment in the opposite direction, and a spring connected to operate said friction-means.

5. In a winding machine, the combination with a traverse-guide adapted to oscillate at substantially right-angles to its di- 85 rection of traverse, of a brake-disk, a friction-band operating in connection with said disk, means operated from the movement of the guide to effect a relative displacement between the disk and its brake-band, and 90 a spring for applying frictional resistance between the band and the brake disk.

6. In a winding machine, the combination with the winding-spindle, of a traverse-guide adapted to recede from the spindle 95 with the growth in the winding, a brake-disk, a friction-band engaging said disk, means operated from the movement of the guide to effect a relative displacement between the disk and its brake band, and a 100 spring operating on said brake-band to apply frictional resistance between the latter and the disk.

7. In a winding machine, the combination with the winding-spindle, of a traverse-guide adapted to recede from the spindle with the growth in the winding, a brake-disk, a friction-band engaging said disk, 105 means operated by the guide to cause a relative movement between the disk and the 110 band as the guide recedes from the winding, and a spring engaging one end of the band to apply friction between the band and the brake-disk.

8. In a winding machine, the combination with a pivoted traverse-guide, of a 115 brake-disk arranged concentric with the axis of the guide, a friction-band engaging the periphery of the disk, means secured to one end of the band and adapted to be 120 moved by the movement of the guide, and a spring connecting said means with the opposite end of the band.

9. In a winding machine, the combination with a pivoted traverse-guide, of a 125 brake-disk arranged concentric with the axis on which the guide swings, an arm pivoted on the axis of the disk, means connecting said arm to be moved by and with the guide, a brake-band secured at one end 130

to the arm and engaging the periphery of the disk, and a spring connecting the opposite end of the band with the arm.

10. In a winding machine, the combination with a pivoted traverse-guide, of a brake-disk mounted concentric with the axis on which the guide swings, a friction-band engaging the periphery of the disk, means connecting one end of the band to move the latter on the disk by and with the movement of the guide, and a spring for resiliently connecting the opposite end of the band with its operating means.

11. In a winding machine, the combination with a pivoted traverse-guide, of a brake-disk mounted concentric with the axis on which the guide swings, a friction-band engaging the periphery of the disk, means for connecting one end of the band to be moved positively by and with the swinging movement of the guide, a spring connecting the opposite end of the band to

be moved with the guide, and means to adjust the tension of the spring.

12. In a winding machine, the combination with a pivoted traverse-guide, of an arm pivoted on the axis of the guide, means connecting said arm and guide to swing together on a common axis while allowing reciprocation of the guide, a brake-disk mounted concentric with the axis of the guide and arm, a friction-band secured at one end to the arm and engaging the periphery of the disk, a spring connecting the opposite end of the band to the arm, and means to vary the point of connection of the spring on the arm.

In testimony whereof I affix my signature in presence of two witnesses.
